UNITED STATES PATENT OFFICE

ALFRED M. LANE, OF ST. LOUIS, MISSOURI

METAL WEATHER STRIP

Application filed November 26, 1928. Serial No. 321,829.

This invention relates to metal weatherstrips particularly adapted for metal windows equipped with swinging sashes.

The invention has for its principal object 5 to provide a simple and efficient metal strip which can be easily and cheaply applied without any alteration of the window frame or sash. Other objects are to render the weatherstrip operative for all variations of the 10 width of the joints between the window frame and sash, to prevent rattling of the sash without binding or without interfering with the easy operation thereof, and to cushion the closing movement of said sash.

15 The invention consists principally in the hereinafter described weatherstrip and in the parts and in the arrangements and combinations of parts hereinafter described and claimed.

20 In the accompanying drawing which forms part of this specification and wherein like symbols refer to like parts wherever they occur,

Fig. 1 is an exterior face view of a metal 25 casement window equipped with weatherstripping embodying my invention;

Fig. 2 is an enlarged vertical cross-section through the window on the line 2—2 in Fig. 1;

30 Fig. 3 is a horizontal cross-section through the window on the line 3—3 in Fig. 1; and

Fig. 4 is a perspective view showing a section of the weatherstrip detached.

Referring to the accompanying drawing, 35 the invention is shown in connection with a metal casement window comprising a window frame A and a sash frame B pivotally mounted at one side of the window frame by means of hinges C so as to swing outward; but the invention is applicable to other types of windows having steel or wooden frames or sashes.

As shown in the drawing, the window frame A is made up of rolled steel frame members 1, each of which comprises a web 2 having lateral side flanges disposed on each side thereof at the inside and outside faces of the frame. As shown in the drawing, the flanges 3 on the outer face of the web 2 of each frame member are of the same width; whereas the flanges on the inner side of said

web are of different width, the narrow flange 4 being located at the outside face of the window frame and forming an inwardly extending rib at the outside edge of the sash receiving opening, and the wide flange 5 being located at the inside face of the frame and forming the inside edge of the sash receiving opening.

The sash frame B is made up of rolled steel frame members 6, each of which comprises a web portion 7 having lateral side flanges 8 and 9 respectively, disposed on the outer face of the web and a single lateral side flange 10, disposed on the inner face of said web. The flanges 8 and 9 on the outer face of the web are of different width, the narrow flange 8 being located at the inside face of the sash and adapted to be overlapped by the wide flange 5 of the adjacent frame member of the window frame in the closed position of the sash; and the wide flange 9 of the sash frame member being located at the outside face of the sash and adapted to overlap the narrow flange 4 of the adjacent frame member of the window frame when the sash is closed. The single flange 10 on the inner sides of the web 7 of each sash frame member 6 is located at the inside face of the sash and cooperates with said webs to form rabbets in which the panes of glass 11 are set. The glass panes are bedded in putty 12 and are held in the rabbets by a retaining strip 13 secured to the web.

The joints between the meeting edges of the window frame A and sash frame B are rendered weatherproof and dustproof by means of resilient metal weatherstrips D. Each of the weatherstrips D comprises a flat main body portion 14 having a hemmed side marginal edge 15, which is perforated, as at 16, to receive a fastening member, and a longitudinally extending side marginal corrugation or hollow rib 17, whose outer wall is extended beyond the flat main body portion of the strip to form a resilient sealing flange 18 which terminates in a hollow bead 19.

The weatherstrips D are mounted in the sash receiving opening of the window frame A with their body portions 14 secured flatwise to the inner faces of the webs 2 of the

100

frame members 1 of said window frame by means of screws 20, which pass through the perforations 16 provided therefor in the hemmed marginal edges 15 of said weatherstrips. The weatherstrips are arranged with their marginal corrugations 16 straddling or embracing the narrow inwardly extending flanges 4 at the outer edge of the sash receiving opening of the window frame and with their resilient sealing flanges 18, which form the outer walls of said corrugations, disposed in front of the outside face of the window frame in position to bear or press against the wide edge flange 9 at the outside face of the sash in the closed position thereof. In such position of the sash, the resilient sealing flanges 18 of the strips are disposed between the overlapped outside flanges 4 and 9 of the window frame and sash, respectively, and bear or press against the opposing faces of said flanges and thus serve to weather-proof the joint or space therebetween.

Among the advantages of my invention is the facility with which it may be applied. In all cases the weatherstrip may be quickly and easily applied to the window without any alteration of the frame or sash, merely by swinging open the sash and applying the strip directly to the face of the sash receiving opening of the window frame. Said strip prevents rattling of the sash without interfering with the easy operation thereof; and it can be readily adjusted for wide joints by rubbing a blunt tool along the outside corner of the hollow rib or channel 16, thereby causing the resilient sealing flange 17 to spring far enough away from the outside face of the window frame to yieldably engage the inside face of the sash flange 9. It is noted that in the closed position of the sash the hollow bead 19 at the free edge of the resilient sealing flange 18 of the weatherstrip overlaps the outer edge of the edge flange 9 of the sash frame and thus serves as a guard to prevent water from being blown between the flange 9 of said sash and the yieldable sealing flange 17 of said weatherstrip.

Obviously, the construction hereinbefore described admits of considerable modification without departing from the invention; therefore, I do not wish to be limited to the precise arrangement shown and described.

What I claim is:

1. The combination of a window frame and an out-swinging sash therefor provided at its outside edge with a portion adapted to overlap the outside edge of the sash opening when the sash is closed of a metal weatherstrip mounted in said sash opening and extending around the outside corner of said sash opening and terminating in a resilient sealing flange disposed in front of the outside face of said window frame in a position to yieldably engage the overlapping outside portion of said sash in the closed position thereof.

2. The combination of a window frame and an out-swinging sash therefor provided at its outside edge with a portion adapted to overlap the outside edge of the sash opening when the sash is closed of a metal weatherstrip mounted in said sash opening and extending around the outside corner of said sash opening and terminating in a resilient sealing flange disposed in front of the outside face of said window frame in a position to yieldably engage the overlapping outside portion of said sash in the closed position thereof, said resilient sealing flange being provided at its free outer edge with a hollow bead adapted in the closed position of said sash to overlap the inside edge of the overlapping outside portion of said sash.

3. The combination of a window frame provided at the outside edge of its sash receiving opening with an inwardly extending rib and an out-swinging sash provided at its outside face with a portion adapted to overlap the outside edge of said sash receiving opening when the sash is closed of a metal weatherstrip mounted in said sash opening and provided with a hollow rib that straddles the rib at the outer edge of said sash opening and has its outside wall extended across the outside face of said window frame to form a resilient sealing flange adapted to yieldably engage the overlapping outside portion of said sash in the closed position thereof.

4. The combination of a metal window frame provided at the outside edge of its sash receiving opening with an inwardly extending flange and a metal sash hinged in said opening to swing outwardly and provided on its outside face with an edge flange adapted to overlap the outside face of the inwardly extending flange at the outside edge of said sash opening when the sash is closed of a metal weatherstrip mounted in said sash opening and provided with a hollow rib that straddles the inwardly extending flange at the outside edge of said sash opening and has its outside wall extended across the outside face of said window frame to form a resilient sealing flange adapted to yieldably engage the overlapping outside edge flange of said sash in the closed position thereof.

5. The combination of a metal window frame provided at the outside edge of its sash receiving opening with an inwardly extending flange and a metal sash hinged in said opening to swing outwardly and provided on its outside face with an edge flange adapted to overlap the outside face of the inwardly extending flange at the outside edge of said sash opening when the sash is closed of a metal weatherstrip mounted in said sash opening and provided with a hollow rib that straddles the inwardly extending flange at the outside edge of said sash opening and has its outside wall extended across the outside face of said window frame to form a

resilient sealing flange adapted to yieldably engage the overlapping outside edge flange of said sash in the closed position thereof, said sealing flange extending beyond the edge of the overlapping outside edge flange of the sash and terminating in a hollow bead.

Signed at St. Louis, Missouri, this 22 day of November, 1928.

ALFRED M. LANE.
